P. P. FARRELLY

RAIL JOINT

Filed Nov. 30, 1925

UNITED STATES PATENT OFFICE.

PETER PHILLIP FARRELLY, DECEASED, LATE OF PORTLAND, OREGON; BY ANNA A. FARRELLY, ADMINISTRATRIX, OF PORTLAND, OREGON.

RAIL JOINT.

Application filed November 30, 1925. Serial No. 72,373.

To all whom it may concern:

Be it known that PETER PHILLIP FARRELLY, deceased, late a citizen of the United States, and late a resident of Portland, in the county of Multnomah and State of Oregon, did invent new and useful Improvements in Rail Joints, of which the following is a specification.

The present invention relates to a rail joint and has for its prime object to provide a structure for efficiently supporting the adjacent ends of aligned rails and to eliminate the usual pounding of the ends of the rails which causes considerable injury thereto, and to the wheels passing thereover.

Another very important object of the invention is the provision of a rail joint of this nature which is exceedingly strong and durable, one which is compact, convenient, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

30 In the drawing:—

Figure 1 is a side elevation of the rail joint embodying the features of my invention.

Figure 2 is a top plan view thereof, and Figure 3 is an end view thereof.

35 Referring to the drawing in detail it will be seen that 5 designates a bridge plate which is adapted to be supported between two ties between which the rails terminate. This plate is provided on each longitudinal edge with a pair of strengthening flanges or ribs 6 upstanding therefrom. On the bottom surface of the bridge plate at the center thereof with respect to its ends, I provide a pair of spaced parallel longitudinally 40 extending strengthening ribs 7, one on each side of the longitudinal median axis of said bridge plate. Attention is called to the feature of my improved structure wherein the strengthening flanges or ribs 6 extend from the ends of the bridge plate and terminate a distance from the intermediate portion thereof. Attention is particularly directed to Figure 1 wherein it will be seen that the thickness of the bridge plate is greatest at 45 its intermediate portion. Said intermediate

portion has its upper surface substantially flat and parallel with the bottom surface while the end portions of the surface are beveled from the intermediate surface downwardly toward the ends so that the ends of the plate are thinner than the intermediate portion. The ends of the rails 8 rest on the intermediate portion of the bridge plate as is disclosed to advantage in Figure 1 taken in connection with Figure 3.

50 The fish plates 9 are bolted one to each side of the webs of the rails as at 10. Bars 11 are constructed to be wider at their centers than at their ends as is apparent from an inspection of Figure 2. These bars have 55 their inner edges shaped to engage the bottom edges of the fish plates 9 and the intermediate portions of these bars are bolted as at 12 to the intermediate portion of the bridge plate 5.

The inclined or beveled surfaces of the bridge plate cause the stress to be placed near the ends of the rails to prevent pounding. The ribs 7 are disposed under the rails 60 on the bottom surface of the bridge plate to 75 receive this stress.

70 In the laying of new tracks it is not necessary to take the joints apart. The joint is merely slipped over the end of one rail and one bolt 10 is put in the bar and then the next rail is slipped into the joint, and then the second bolt 10 is engaged with the second bar. Spike receiving openings 13 are 75 provided in the bridge plate so that the same may be secured to the ties upon which it 80 rests.

85 It is thought that the construction, utility, advantages, convenience, and the like of the invention will now be clearly understood without a more detailed description thereof.

90 The present embodiment of the invention has been disclosed in detail merely by way of example since in actual practice it attains the features of advantage enumerated as desirable in the statement of the invention and 95 the above description. It is apparent that numerous changes in the details of construction, and in the combination and arrangement of parts may be resorted to without departing from the spirit or scope of the invention as hereinafter claimed or sacrificing any of its advantages.

100 Having thus described the invention, what I claim as new is:—

110 1. A bridge plate of the class described

including an elongated body having its intermediate portion thicker than its ends so as to provide an intermediately disposed upper flat plane surface merging into downwardly inclined end surfaces, strengthening flanges on the longitudinal edges of the body rising upwardly therefrom, there being two flanges on each longitudinal edge having their inner ends spaced, and a pair of depending ribs on the bottom surface of the body extending longitudinally thereof, one on each side of the longitudinal axis thereof.

2. A rail joint of the class described including a bridge plate having its intermediate portion thicker than its ends so as to provide an intermediate flat plane surface and downwardly inclined end surfaces merging therefrom, and bars adapted to be attached to the bridge plate to extend longitudinally thereof.

3. A rail joint of the class described, including in combination, a bridge plate having an elongated rectangular body portion

thicker at its intermediate part than at its ends so as to provide an intermediate flat surface merging into downwardly inclined end surfaces, a pair of strengthening flanges on each longitudinal edge of the body portion rising therefrom and spaced at their inner ends, a pair of depending strengthening ribs extending from the bottom surface of the body portion, one to each side of the longitudinal axis thereof and having their ends spaced from the ends of the body portion, a pair of fish plates adapted to be engaged with the adjacent ends of a pair of aligned rails, a pair of bars, means for bolting the bars to the intermediate portions of the body portion so that the inner edges of the bars engage the lower edges of the fish plates.

In testimony whereof I affix my signature.

ANNA A. FARRELLY,
*Administratrix of Peter Phillip Farrelly,
Deceased.*
